United States Patent Office.

WILLIAM KERR, OF PHILADELPHIA, PENNSYLVANIA, ASSIGNOR TO
ISRAEL FOSTER, OF SAME PLACE.

Design No. 4,035, dated May 17, 1870.

DESIGN FOR A CARPET-PATTERN.

The Schedule referred to in these Letters Patent and making part of the same.

I, WILLIAM KERR, of Philadelphia, county of Philadelphia, State of Pennsylvania, have invented or produced a Design for a Carpet-Pattern, of which the following is a specification.

The figure in the accompanying drawings represents my design for a carpet, the remainder of the pattern being merely a repetition of that which appears.

The design consists of a square or diamond-shaped member, A, of a circular member, B, the outline of which is made up of a series of small curves instead of one continuous curve, and of a small square member C.

These members, A, B, and C, are surrounded by curved ribs *a*, arranged in such a manner as to form a circular figure, F, surrounding the member C, and

elliptical figures H between each of the figures A and B.

Irrespective of any minor ornamentation, or of the colors employed,

I claim—

The design for a carpet-pattern, consisting of members A B and C, and of curved ribs *a*, the whole being arranged substantially as described, and as represented in and by the accompanying drawings.

In testimony whereof I have signed my name to this specification in the presence of two subscribing witnesses.

Witnesses:
CHARLES SENIX,
HARRY SMITH.

WILLIAM KERR.
